PICTURE FRAME AND SUPPORT

Nathaniel Turan, Maspeth, N. Y.

Application November 14, 1944, Serial No. 563,361

7 Claims. (Cl. 40—152;1)

1

It is among the objects of the invention to provide a simple, unitary, inexpensive easel picture frame that may be stamped from a single blank of any suitable material, that may be sold flat and may be readily set up for securely holding a picture in easel supported position and as readily collapsed when desired.

According to the invention, the unitary blank, preferably of ornamental paper board or flexible resin-impregnated textile fabric or the like, includes an open frame panel, preferably rectangular, having a base flap folded upward thence outward, the up-folded portion constituting a clamping strip for retaining in place in-folded flap means serving as a backing for a picture in the frame, while other flap means folded inward is releasably locked by and against the outer part of the base flap at an angle to the panel to serve as an easel.

In the accompanying drawings in which is shown one of various possible embodiments of the several features of the invention.

Fig. 1 is a perspective view of the easel frame set up for use as seen generally from the front.

Fig. 2 is a view of the frame similar to Fig. 1 as seen generally from the rear.

Fig. 3 is a view in longitudinal cross section taken on line 3—3 of Fig. 1.

Fig. 4 is a transverse sectional view taken on line 4—4 of Fig. 3, and

Fig. 5 is a view of the blank from which the frame may be made.

Referring now to the drawings, the frame panel 10 is shown rectangular and has an opening 11 of desired shape to expose the picture 12. Protruding from all four edges of the panel are flaps. One of these is a relatively short base flap 13 having a root 14 preferably the full width of the frame panel 10 and having a transverse fold line 15 defining a clamping strip 16. This clamping strip is folded inward as shown in Fig. 3 against the lower part of the panel 10 to retain in position, the picture backing flap 17, which desirably protrudes from the upper edge of the frame and is substantially the full height of the frame panel 10, it being desirably only slightly narrower immediately beyond the fillet 18 at its root as shown, to be spaced slightly from the roots or fold lines 19 of the lateral flaps 20 which extend for the entire height of the panel frame 10.

Preferably the area 21 of the base flap 13 beyond the transverse fold line 15 is of equilateral trapezoidal shape and its sides or legs have locking tabs 22 co-acting with corresponding slits

2

23 in the lateral flaps 20. These slits are preferably U-shaped as shown to be at the flat ends of short tongues 24 in the lateral flaps.

The frame may be of any suitable sheet material with ornamental facing and embossments to simulate any desired effects. The frame may be sold as an initially flat unit with its four flaps 13, 17, 20 and 20 folded inward against the back of panel frame 10. It may be readily set up for use by folding the top flap 17 inwardly thereby to back the picture 12, then folding the base flap 13 upward and folding the trapezoidal area 21 thereof, outwardly, and introducing the tabs 22 into the slits 23 of the lateral flaps 20, which are folded inward against the sides of the trapezoidal outstanding base flap area 21. In this manner the lateral flaps 20 are buttressed and locked against the sides of the trapezoidal base flap 21, maintaining the clamping strip 16 in secure engagement with the lower end of the in-turned top or picture backing flap 17, securely to hold the picture 12 in place. The lower edges of the lateral easel flaps 20 are desirably oblique as at 25, so as to retain the picture at the desired slant suggested in Fig. 1.

The tongues 24 resiliently and securely grip the tabs 22 and thus the easel support will not be collapsed by every touch and it is quite stable in service. Yet the frame may be readily opened by pushing apart the flaps 20 for release of the tabs 22 to permit replacement of a picture, or the flaps may be flattened in back of the face panel for storage.

As many changes could be made in the above article, and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

- 45 1. An easel frame consisting of a unitary blank of sheet material, comprising an open frame panel having flaps unitary therewith and including a base flap with a transverse fold line defining a clamp strip to underly the panel, other flap means held in place by said clamp strip against the back of the panel for backing a picture in the frame, and easel flap means, said base flap having means for securing said easel flap means in operative position.
- 50 2. A picture frame comprising a unitary blank

including a rectangular open frame panel, flaps hinged to the four edges thereof, including a base flap, lateral flap means and top flap means, said base flap having a transverse fold determining a clamping strip, the outer portion of said flap having lock tongue means, one of said flap means being folded inward over the back of the frame panel for backing a picture and being retained in place by said clamping strip, the other flap means being releasably held by said lock tongue means against the outstanding part of said base flap and serving as an easel.

3. An easel picture frame, comprising a unitary blank of sheet material, including a rectangular open frame panel, unitary flaps protruding from the edges thereof and including a top flap serving as a backing for a picture, lateral flaps serving as an easel and a base flap having a transverse fold defining a clamping strip for retaining the backing flap and having lateral locking means for retaining the easel flaps in operative position.

4. A unitary easel picture frame, comprising an integral blank of sheet material, including a rectangular open frame panel having flaps along the full length of each edge thereof, and including a top flap, lateral flaps and a base flap, said top flap being of substantially the area of the frame panel and serving as a backing for a picture, said base flap being shorter and having a transverse fold near its root, the area between said fold and the root of said flap defining a clamping strip for retaining the backing panel, the body of said base flap being folded outward and having lateral locking tongues releasably fitting in corresponding slits in the lateral flaps, the latter forming an easel support for the frame.

5. A picture frame comprising a unitary blank of sheet material including a rectangular open frame panel, unitary flaps, including a top flap, lateral flaps and a base flap hinged to the respective edges of said panel, each having a hinging root of substantially the full length of the corresponding panel edge, said top flap being of substantially the full height of said panel and laterally spaced in infolded position slightly from the roots of said lateral flaps, said base flap having a transverse fold defining a clamping strip there-

below and having an outer equilateral trapezoidal part beyond said fold, with lateral tabs at the sides thereof, the lateral flaps having slits for releasably accommodating said tabs to retain the lateral flaps against said sides and to maintain the clamping strip pressed against said inturned top flap.

6. An easel picture frame, comprising a unitary blank of sheet material, including a rectangular open frame panel, unitary flaps protruding from the edges thereof and including a top flap serving as a backing for a picture, lateral flaps serving as an easel and a base flap having holding means for retaining the backing flap in position and having lateral locking means for retaining the easel flaps in operative position, said lateral locking means holding said easel flaps so that they incline inwardly and rearwardly toward each other.

7. An easel picture frame, comprising a unitary blank of sheet material, including a rectangular open frame panel, unitary flaps protruding from the edges thereof and including a top flap serving for a backing for a picture, lateral flaps serving as an easel and a base flap having holding means for retaining the backing flap in position and having lateral locking means for retaining the easel flaps in operative position, said base flap having a substantially vertical portion serving as said holding means and a trapezoidal shaped substantially horizontal portion carrying said locking means.

NATHANIEL TURAN.
